(57) **CLAIM**

The design for a brush for cosmetic use, as shown and
described.

DESCRIPTION

FIG. 1 is a left side view of the claimed design.

FIG. 2 is a front view of the claimed design.

FIG. 3 is a top view of the claimed design.

FIG. 4 is a rear view of the claimed design.

FIG. 5 is a right side view of the claimed design.

FIG. 6 is a bottom view of the claimed design; and,

FIG. 7 is an isometric view of the claimed design.

The broken-line showing of the rear surface forms no part of
the claimed design.
